DESIGN FOR A LAMP SHADE

Faust Farinacci, St. Albans, N. Y.

Application September 9, 1939, Serial No. 87,106

Term of patent 14 years

To all whom it may concern:

Be it known that I, Faust Farinacci, a citizen of the United States, residing at 188-52 114th Drive, St. Albans, L. I., State of New York, have invented a new, original, and ornamental Design for Lamp Shades, of which the following is a specification, reference being had to the accompanying drawing, forming part thereof.

Figure 1 is a side view; Figure 2 is a plan view, and Figure 3 is a fragmentary view taken on line 3—3 of Figure 1 of the lamp shade showing my new design.

I claim:

The ornamental design for a lamp shade, as shown.

FAUST FARINACCI.
